ATTORNEY

UNITED STATES PATENT OFFICE

BENJAMIN MAYER, OF NEW YORK, N. Y.

THEFTPROOF POCKET

Application filed October 25, 1928. Serial No. 314,858.

This invention relates generally to clothing and has more particular reference to a novel pocket therefor.

The invention has for an object the provision of an article of the class mentioned, which is of simple durable construction, desirable in use and efficient in action, and which can be manufactured and sold at a reasonable cost.

10 The invention proposes the use of a partition arranged within a pocket for dividing it into an inner and outer pocket section and a means for closing one of these sections. With this construction it is possible to carry valuable articles in the pocket which may be closed and other articles in the pocket section left normally opened. Articles carried in the closable section may not be readily lost and thus adds to the value of the pocket.

20 For further comprehension of the invention and of the objects and advantages thereof, reference will be had to the following description and accompanying drawings, and to the appended claims in which the various novel features of the invention are more particularly set forth.

In the accompanying drawing, forming a material part of this disclosure:—

Fig. 1 is an elevational view of cloth material and a pocket applied thereto according to this invention.

Fig. 2 is a fragmentary perspective view thereof, looking in the direction of the arrows 2—2 of Fig. 1.

35 Fig. 3 is a fragmentary horizontal sectional view, taken on the line 3—3 of Fig. 1.

Fig. 4 is a vertical sectional view, taken on the line 4—4 of Fig. 3.

Fig. 5 is a vertical sectional view, taken on 40 the line 5—5 of Fig. 3.

Fig. 6 is a view similar to Fig. 2, but disclosing a modification thereof.

Fig. 7 is a side view of a pair of trousers with the invention applied thereto.

45 The reference numeral 10 indicates generally a piece of material hereafter named as a front piece of material, and numeral 11 indicates generally a piece of material hereafter called a rear piece of material. These materials are joined together by stitches 12 and 13.

The stitches 12 and 13 are spaced from each other for providing a pocket opening 14. The stitches 12 extend from the top of the pocket opening upwards, and the stitches 13 from the bottom of the pocket opening downwards. Transverse stitches 16 determine the bottom of the pocket opening and transverse stitches 15 the top of the pocket opening. The pocket material 17 is bent at a vertical side such as side 18 hereafter referred to as the inner side of the pocket, and the ends of this material forming the front side of the pocket are disposed in the vicinity of the seam formed by the materials 10 and 11.

55 The front material 10 is formed with a rearward flap 19 engaging over one of the front edges of the pocket material 17. The other front edge of the pocket material is secured by stitches 20 and 21 to the material 11 and to an auxiliary pocket strip 22 attached on the 60 material 11. A partition 23 of cloth material divides the pocket into an inner pocket section 24 and an outer pocket section 25. Stitches 26 secure the inner end of the partition to the material of the pocket. An edge 65 binding strip 27 is engaged over the outer edge of the partition 23.

70 As seen in Fig. 5, the transverse stitches 15 and 16 pass thru all of the materials used in this article. These stitches, as before stated, 75 determine the top and bottom of the pocket opening. Below the stitches 16, the material 11 has a slot 28 so that the portion below the slot may be attached onto the material 10 while the portion above the slot is engaged by 80 the auxiliary strip 22 of the pocket 17.

85 Buttons 29 are attached on the auxiliary strip 22 and are engageable in buttonholes 30 formed in the edge binding 27. When the edge binding is engaged upon these buttons 90 the inner pocket section 24 is closed. This condition of the article is illustrated in Fig. 2. It should be noted that the outer pocket section 25 is available for use while it is necessary 95 first to disengage the buttons 29 before the inner pocket section may be used.

99 Stitches 31 close the bottom of the pocket material 17 and stitches 32 close the sides of this material below the stitches 16 and at the outer end of this material. Referring to Fig. 100

1, it is seen that at the side 18 the pocket material 17 is closed by reason of being bent, and the bottom of the pocket material is closed by stitches 31 while the side is closed by stitches 32 up to the bottom of the pocket opening 14. 5 The stitches 12 serve to close the pocket material 17 above the stitches 15, i. e., above the top of the pocket opening.

Articles of considerable value such as currency bills may be placed within the inner pocket section and securely carried by closing this section as before stated. Other articles of a lesser value may be carried in the outer section 25 which is normally open. 10 Another valuable feature contributed by this construction consists in the fact that should one of the pocket sections become worn thru by reason of carrying coins or keys in it, the other section can be used without danger of 15 losing articles.

In the modified form of the device illustrated in Fig. 6, one of the buttons used in closing the inner pocket section is arranged for moving, this button being indicated by 20 numeral 33. Before button 33 may be engaged in its buttonhole for closing the inner pocket section, it is necessary to draw this button downwards and advantage is taken of this principal for providing an indication 25 whether the inner pocket section is closed or left open.

A guide 34 is attached onto the auxiliary strip 22 which has a slot 35 so that the button 33 may be disposed on the outer side of the 30 auxiliary strip, and a slide 36 arranged in the guide 34 for supporting the button 33. A bar 37 connects with the slide 36 and with an arm 38 pivoted as at 39 onto a plate 40 attached on the material 10. A co-axial 35 spring 41 mounted on the pivot 39 acts between the plate 40 and the arm 38 for normally urging the free end of the arm downwards. A patch cover 42 is attached on the free end of the arm. It should be noted that 40 a portion of the arm 38 extends to the outer side of the material 10 and the patch cover is attached on this extended end. A conspicuous patch 43 is secured on the material 10. When the inner pocket section is opened, the 45 patch cover 42 is in a lowered condition so that the conspicuous patch 43 is visible. When the movable button 33 is engaged in its buttonhole the cover 42 is moved upwards against the action of the spring 41 for covering patch 43.

While I have shown and described the preferred embodiment of my invention, it is to be understood that I do not limit myself to the precise construction herein disclosed and 60 the right is reserved to all changes and modifications coming within the scope of the invention as defined in the appended claims.

Having thus described my invention, what 65 I claim as new, and desire to secure by United 85 States Letters Patent is:—

1. In combination with a theft proof pocket, front material formed with a patch, a patch cover of equal size and similar shape as that of the patch, a lever supporting the patch cover at one of its ends, a plate attached to the front material and pivotally supporting said lever intermediate of its ends, a spring for normally urging patch cover from over the patch, a bar pivotally attached at one of its ends on the other end of the said lever, a slide joined to the other end of the bar, a guide for the slide, an auxiliary strip attached to the front material and supporting the said guide, and a button attached on the guide and arranged to engage a button hole for closing the pocket and for simultaneously holding the patch cover over the patch. 70

2. In combination with a theft proof pocket, front material formed with a patch, a patch cover of equal size and similar shape as that of the patch, a lever supporting the patch cover at one of its ends, a plate attached to the front material and pivotally supporting said lever intermediate of its ends, means for normally urging patch cover from over the patch, a bar pivotally attached at one of its ends on the other end of the said lever, a slide joined to the other end of the bar, a guide for the slide, an auxiliary strip attached to the front material and supporting the said 80 guide, and a button attached on the guide and arranged to engage a button hole for closing the pocket and for simultaneously holding the patch cover over the patch. 85

In testimony whereof I have affixed my 90 signature.

BENJAMIN MAYER.
